The ornamental design for the rotary cutter, as shown and described.

DESCRIPTION

FIG. 1 is a front elevational view of a rotary cutter showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof showing the blade guard in an alternate position; and,

FIG. 8 is a rear elevational view of the rotary cutter shown in FIG. 7.

The broken line showing in the drawings is for illustrative purposes only and forms no part of the claimed design.
